ANTIPERSONNEL ARTILLERY MINE

Clarence C. Hicks, Milwaukee, Wis.

Application November 1, 1945, Serial No. 626,157

3 Claims. (Cl. 102—68)

(Granted under the act of March 3, 1883, as amended April 30, 1928; 370 O. G. 757)

1

The invention described herein may be manufactured and used by or for the Government for governmental purposes without the payment to me of any royalty thereon.

My invention relates to improvement in anti-personnel mines.

An important object of my invention is to provide a delayed action anti-personnel mine, in combination with an artillery projectile, for example, one similar to the base-ejection shell now in use for firing smoke, propaganda leaflets, and medical supplies but rearranged and adapted to my invention, which may be conveyed to and placed accurately in any desired area by means of artillery fire.

The object sought in the use of mines of this nature, placed by means of artillery fire, is the neutralization of enemy personnel during an attack, and the ability to maintain this neutralization for any desired period of time through the operation of a delay fuze. In other words, a volley or series of volleys would deliver a large number of these mines into the desired area; the mines would continue to detonate at such intervals as may be desired since the delaying device can be arranged for delays ranging from a few seconds to several hours. Thus, effective neutralization may be obtained with a minimum of effort and ammunition.

Such mines can also be effectively used in defensive barrages since whole areas of defense can be saturated to hinder and delay an enemy using any such area as an avenue of approach for a considerable period of time with a minimum expenditure of ammunition.

The effect obtained is greatly enhanced at night, or when the mines are placed in areas where deep grass or underbrush would prevent their detection. The mines may also be arranged to prevent disarming if located, as will be herein-after pointed out.

Other effects and advantages of the invention will become apparent during the course of the following description.

The accompanying drawings, forming part of the specification, illustrate the manner in which I attain these objects. Similar numbers are used to designate like parts throughout the specification and drawings. In these drawings:

Figure 1 is a longitudinal central section of a shell or projectile embodying the invention, with the enclosed anti-personnel mines shown in elevation, and including an elevation of a projectile fuze.

Figure 2 is a transverse section of an anti-personnel mine, taken on line 2—2 of Figure 1, and shows the delaying mechanism of the mine.

2

Figure 3 is a vertical longitudinal section of an anti-personnel mine taken on line 3—3 of Figure 2, and includes a partial elevation of the activating rod and nut, and,

5 Figure 4 is a transverse section through the firing pin, taken on line 4—4 of Figure 2.

Referring in detail to the accompanying drawings, the numeral 5 indicates a base-ejection type of shell or projectile similar to a standard smoke shell. The shell comprises a steel body 6, a base plug 7, a rotating band 8, and adapter 9, attached to the body 6 by screw threads 10 and arranged to engage a nose fuze 11 which may be one of either the superquick or time type. A powder bag 15 12 containing an expelling charge of black powder is located in the cavity formed by the walls of the adapter 9, and is backed up by a perforated anchor plate 13.

The numeral 14 designates a mine of the type described herein, comprising a body 15 which may be of steel tubing, or cast steel serrated for better fragmentation if desired, said body being arranged with a recess 16 on its inner circumference formed by projections 18 on the said inner circumference, having an integrally cast pin 19 on its top surface and a hole 20 on its bottom surface to engage an adjacent mine within the shell 5 and prevent rotation of the mines while the shell is in flight, and also provided with a screw engaging plug 21 on either side to permit filling the charge chamber 17 with an explosive charge 22, and a screw engaging plug 23 for insertion of the sleeve 24.

The sleeve 24 furnishes housing for the operating mechanism of the mine. It is generally circular in cross-section and has a transverse semi-cylindrical projection 25 near one end to form part of an open passage 26 extending through the mine 14 and is provided with flame holes 27 at

40 the opposite end to allow passage of flame into the charge chamber 17 when the detonator 28 housed within the sleeve cavity 29 at the end nearest the plug 23 is detonated by the action of a firing pin 30 igniting a primer charge 31, also housed within the said cavity 29, through an orifice 32 in the adjacent end of a copper housing 33 of the same cross-section as the inside of the sleeve 24 and fitting snugly therein, positioned to partially close the passage 26 formed by the bulbous projection 25.

45 A glass ampule 34 containing a corrosive acid is fitted tightly within the copper housing 33 at the end adjacent the bulbous projection 25 and is held thus positioned and partially blocking the passage 26 by means of a suitable spacer 35 and the end of the copper housing 33 which is shaped to conform to the end of the ampule 34.

50 A collapsible coil spring 36, is posi-

55 tioned to hold the ampule 34 in place and to hold the sleeve 24 in place.

tioned between the firing pin 30 and the spacer 35 and is held in compression by a restraining wire 37 arranged in such manner within the housing that it will come in contact with the acid contained in the ampule 34 after the ampule is broken. The firing pin 30 is provided with a transverse hole 38 so positioned that when aligned with an opening (not shown) in the top surface of the mine body 15, a safety pin 39 may be inserted. The safety pin 39 keeps the mine unarmed until it is placed in the shell 5, and provides enough slack in the restraining wire 37 to allow the firing pin 30 to move ahead a sufficient distance to bring the hole 38 out of alignment with the opening in the top surface of the mine body 15 when the said mine is ejected from the shell 5 and the firing pin 30 is freed from the restraining influence of a safety rod 40. A safety rod as 40 is fixed permanently in the perforated baffle 13 and positioned so that the firing pin 30 will remain in the same position after the mine is placed in the shell 5 and the safety pin 39 is withdrawn thus retaining the slack in the restraining wire 37. A suitable transverse opening 41 is provided in top and bottom of the mine to permit passage of the safety rod 40.

An activating rod 42 permanently attached to the perforated baffle 13 and positioned so that an activating head 43, whose largest diameter is slightly smaller than the diameter of the passage 26, attached to the said activating rod by tight screw engagement (not shown) after the mines 14 have been loaded into the shell 5 will deform the copper housing 33 during the ejection of the mine 14, thus breaking the enclosed glass ampule 34 and allowing the acid contained therein to perforate the restraining wire 37. Spacers 44 which may be made of steel or other appropriate material, one of which is arranged with suitable openings to allow passage of the safety rod 40 and the activating rod 42, are provided within the shell to separate the enclosed mines 14 from the anchor plate 13 and the base plug 7, respectively.

The operation of the anti-personnel mine is as follows: Upon detonation of the fuze 11, which as heretofore stated may be either an instantaneous impact or a time fuze, the expelling charge of black powder contained in the powder bag 12 is exploded and the force of the explosion, transmitted through the perforations in the anchor plate 13, blows out the base plug 7 of the shell 5 and ejects the mines 14. The safety rod 40 and the activating rod 42 with activating nut 43 attached remain attached to the anchor plate 13. As a mine 14 is ejected from the shell 5 each copper housing 33 is pressed against the activating head 43 forcing their walls inwardly and crushing the ampules 34 containing the corrosive acid permitting the released acid, to commence its corrosive action on the restraining wire 37, and at the same time the firing pin 30 is freed from the restraint of the safety rod 40 permitting the compressed spring 36 to relax to the limit of the slack in the restraining wire 37, thus advancing the firing pin 30 a distance sufficient to bring the hole 38 out of alignment with the hole in the top of the mine 14 and preventing insertion of a disarming pin. Corrosive action of the acid continues until complete rupture of the restraining wire 37, the period of time required to bring about such complete rupture being governed and regulated by varying the strength of the acid used, the thickness of the wire, or both, and may range from

5 a fraction of a second to several hours. Upon complete rupture of the restraining wire 37, the compressed spring 36 will relax and drive the point of the firing pin 30 through the orifice 32 and against the primer charge 31, igniting it. The flame of the primer charge ignites the detonator charge 28, the flames being carried through the flame holes 27 and into the explosive charge 22 in the charge chamber 17, thus exploding the 10 mine.

15 From the foregoing it should be evident that the number of mines contained in the shell 5 is dependent upon the size and caliber of the mines used, and the mines included may be of varying sizes within the same shell. Type of mine used 20 may also vary and may include such anti-personnel mine types as those utilizing metal balls within the body of the mine. By adding a small parachute as now used with flares, such mines 25 might be used in maintaining an effective aerial barrage within a given air area. Therefore, it is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described the invention, I claim:
30 1. A mine-laying device comprising a container, a yieldable closure on one end of the container, an explosive ejection charge at the other end of the container, individual mines nested in the container between the closure and ejection charge, said mines having aligned openings longitudinally of the container, a rod member secured in the container at the end having the ejection charge, passing through said aligned openings and having a headed portion on the end adjacent the closure, an explosive charge in each mine and delay firing means, therefor, including a detent means lying in the path of and responsive to relative motion between said mines and the headed portion of said rod for release of said 45 firing means.

2. The device of claim 1, said firing means comprising a spring-biased firing pin, and said detent means comprising a frangible ampule containing a corrosive fluid for release of said spring on rupture of said ampule by said headed portion.

3. The device of claim 2, said container comprising a safety member held in the portion of the container adjacent the ejection charge and 55 passing through each mine in position to obstruct the path of the firing pin and holding the pin in tension beyond that defined by the detent means, whereby on removal of said safety member the pin will move to prevent reinsertion of a safety member.
